(57) **CLAIM**

The ornamental design for an articulated utility cart, as shown and described.

DESCRIPTION

FIG. 1 is a front right isometric view of the articulated utility cart of the present invention;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof; and,

FIG. 8 is a perspective view showing the articulated utility cart in an alternate position.

The portions of the articulated utility cart illustrated in broken lines form no part of the claimed subject matter.

1 Claim, 7 Drawing Sheets

FIG. 2

FIG. 3

FIG. 7

FIG. 6
